UNITED STATES PATENT OFFICE.

JOHN A. WHITTINGTON, OF ATLANTA, GEORGIA.

MULTICOLOR-PRINTING DEVICE.

Application filed March 18, 1925. Serial No. 16,412.

The present invention relates to chromatic or multi-color printing devices, and aims to provide a novel and improved device of that kind.

5 The device is intended for use in a printing press, preferably in a chase with other types, and is adapted to print letters, words, numerals or other characters in a color contrasted to the color of ink used for the regular impressions, in order that the portion 10 of the printed matter which is of different color will attract attention, such as for use in headlines, advertisements, and the like. The device may thus constitute a part of the 15 type set-up in a printing chase, and may have portions to make impressions on the sheets in the same color as the impressions made by the regular type, cuts, etc., and, in addition, the device has means for printing 20 characters in a different color. Thus, if black ink is used for the regular impressions, the device has portions to make impressions in such black ink, and the device also makes a simultaneous impression in a different 25 color, for example, red.

One object of the invention is the provision of such a device utilizing a ribbon or web for making the contrasting color impressions, in order to eliminate the use of an 30 inking pad, font, reservoir, or the like, and also eliminating the necessity for the contrasting color type being movably mounted.

Another object is the provision of such a device wherein the type that make the contrasting color impressions are fixed in the device, without requiring movement thereof relatively to the device and other type, although the contrasting color type may be removed for replacement.

40 A further object is the provision of novel means for mounting, controlling and actuating the contrasting color ribbon.

A still further object is the provision of novel means for moving the ribbon step by step as successive impressions are made, in order to present successive portions of the ribbon for making the impressions.

50 Still another object is the provision of means for reversing the movement of the ribbon when it completes its limit of feeding movement in one direction, in order that the ribbon will alternately be moved in opposite directions.

It is also an object of the invention to provide a printing device of the kind indicated comprising a novel construction and assem-

blage of the component elements, and including novel details, in order to enhance the utility and efficiency of the device.

With the foregoing and other objects in view, which will be apparent as the description proceeds, the invention resides in the construction and arrangement of parts, as hereinafter described and claimed, it being understood that changes can be made within the scope of what is claimed; without departing from the spirit of the invention.

The invention is illustrated in the accompanying drawings, wherein—

Figure 1 is a perspective view of the improved printing device.

Fig. 2 is a plan view thereof with the top plate or primary impression member removed.

Fig. 3 is a bottom view of said top plate 75 or primary impression member.

Fig. 4 is a side elevation of the device with the near side plate or wall removed.

Fig. 5 is a longitudinal section on the line 5—5 of Fig. 2, portions being shown in 80 elevation.

Figs. 6, 7, 8, 9 and 10 are cross sections on the respective lines 6—6, 7—7, 8—8, 9—9 and 10—10 of Fig. 4.

Fig. 11 is a perspective view of one of the 85 side plates or walls.

The device comprises in a way, a secondary or supplementary chase, to be used within a regular printing chase, with other type, but the present device may be used 90 by itself in some instances although not so intended for general use. The body of the device is in the form of a rectangular case, and comprises the bottom 14, end walls 15 integral with the bottom, side walls or plates 95 16, and transverse end blocks 17 secured on the bottom 14 and against the end walls 15.

A top plate or primary impression member 18 is disposed above the body and serves to shield or protect the working parts therein, said plate or member 18 being preferably of the same shape as the body, and being mounted for movement toward and away

from the body. The plate or member 18 is 100 at the top, as shown and described, although the device may assume inverted or other positions in various styles of printing presses.

The impression plate or member 18 is provided at its ends with depending shanks or 105 portions 19 which are slidable in channels or grooves 20 with which the blocks 17 are

110

formed adjacent to the end walls 15, thereby guiding the plate 18 for up and down movement. Such movement is limited by the provision of vertical slots 21 in the shanks 19, 5 and stop pins or screws 22 extending through the end walls 15 and into the blocks 17, said screws extending through the slots 21 to limit the movement of the plate 18 away from the body.

10 The plate 18 is raised yieldingly by means of coiled springs 23 confined between the plate 18 and body, the blocks 17 having recesses or sockets 24 to receive said springs which are located near the four corners of 15 the body. The springs 23 offer sufficient resistance in order to prevent the plate 18 from being depressed the full amount when said plate contacts with the soft inking rollers of the press as will hereinafter more 20 fully appear, although the plate 18 is compelled to yield when brought against the platen when the impression is made.

25 The plate 18 has a pair of longitudinal lips 25 struck upwardly therefrom and converging upwardly toward one another, with a longitudinal slot 26 between them. The edges of the lips 25 provide primary impression portions or bars to receive the black or other usual ink from the inking roller or 30 rollers so as to make two parallel lines or bars on the sheet when the regular type impressions are made. It will be understood, however, that the plate 18 may carry other suitable impression portions for making 35 regular color impressions on the sheets. As shown, the plate 18 has a downturned marginal rim or flange 27 which strengthens and stiffens said plate, and reinforcing bars or strips 27' are secured to the bottom surface of the plate 18 at the ends thereof to 40 seat on the springs 23.

45 The secondary or contrasting color impression member 28 may be a solid line of type, individual type, a line cut, engraving, or the like, and may have suitable letters, words, numbers or other characters, and the secondary impression member 28 is accommodated by a receptacle 29 mounted in the body of the device. Said receptacle is of 50 elongated form, as shown, and disposed longitudinally of the body at the longitudinal center line, and said receptacle has its lower edge portion engaging through the bottom 55 14. Said receptacle is open at the top and bottom, in order that the member 28 may be readily inserted into the receptacle or holder 29 from the bottom, and in order that the face of said member will be exposed at the top of the device through the slot 26. The 60 impression member 28 is type high, so as to correspond with the regular type amongst which the device is used, and the top plate or primary impression member 18 is raised by the springs 23 so that the lips or impression portions 25 are normally above the level 65

or plane of the type faces. The receptacle 29 has outstanding flanges 30' at its opposite sides secured on the bottom 14 of the body, whereby said receptacle is secured rigidly to the body as a part thereof, and the impression member 28 is therefore non-movable relatively to the device, the same as the regular type, and said member 28 remains in upright position. The member 28 may be readily withdrawn from the body through the bottom thereof when the device is removed from the printing press or the chase thereof, in order that different impression members may be used interchangeably in the receptacle 29.

70 The ink, pigment or other color medium for making the contrasting color impressions is supplied by a ribbon or web 30 of fabric or other material containing, by absorption or otherwise, the ink or pigment. The ribbon or web 30 extends over and across the face of the type or impression member 28, in order that the impression by the member 28 is made through the ribbon or web, similar to the impressions made by a typewriter, excepting that the ribbon 30 of the present device remains in contact with the face of the type or impression member 28.

75 Provision is made for accommodating a ribbon of considerable length and for moving the ribbon so as to present successive portions thereof for making the impressions. For this purpose, parallel longitudinal shafts 31 and 32 are disposed at the opposite sides of the receptacles 29, or between said receptacle and side plates 16, longitudinally of the device, and said shafts provide drums or spools on which the ribbon is wound in reverse directions, as clearly seen in Fig. 8. The shafts may be slotted to receive the terminals of the ribbon or may have other means for receiving said terminals in order that the ribbon will be wound on said shafts. The terminals of the shafts 31 and 32 are mounted for rotation in slots 33 with which the inner sides of the blocks 17 are formed, in order to mount said shafts for rotation. Said slots 33 extend to the ends of the blocks 17 or the opposite sides of the device in order that said shafts may be readily inserted into and removed from said slots when the side plates or walls 16 are removed so that the ribbon may be removed and replaced when worn out. The side plates 16 have inwardly extending fingers 34 that slide into the slots 33 when the side plates are moved against the edges of the bottom 14 and end walls 15, thereby confining the shafts 31 and 32 between the inner ends of the slots 33 and fingers 34. The terminals of the shafts thus provide trunnions, received by the sockets formed by the inner end portions of the slots 33 beyond the fingers 34. When the side plates 16 are assembled with the blocks 17, and are held 80

in place; such as by being confined within the type of a printing press chase, the shafts 31 and 32 will be retained in proper position, although said shafts are free to rotate. When the device is liberated from the printing press, so that the side plates 16 can be removed, this will permit the shafts 31 and 32 to be withdrawn from the slots 33 for inspecting or changing the ribbon.

10 Tension means are provided in order to keep the ribbon 30 under tension so that it will bear with desired tension on the face of the type or impression member 28, and to also prevent the ribbon from unwinding too freely from the shafts. The tension means comprise leaf springs 36 seated on the bottom 14, for the contact of friction disks 35 secured on the shafts 31 and 32 adjacent to the one block 17. The leaf springs 36 are disposed transversely below the shafts and are secured at their outer ends, as at 37, on the bottom 14. The intermediate portions of the leaf springs are offset upwardly, as at 38, and are slightly concaved longitudinally for contact with the lower portion of the disks 35, as seen in Fig. 7. The disks 35 may be readily moved over and off the leaf springs in inserting and removing the shafts 31 and 32, and when the shafts are inserted, the disks 35 being moved over the leaf springs will depress the portions 38 slightly so as to create the desired tension due to the frictional contact of the leaf springs 36 and edges of the disks 35. The leaf springs will also prevent the accidental dropping of the shafts 31 and 32 from the slots 33 when the side plates 16 are removed, thereby requiring that the shafts be withdrawn with sufficient force to disengage the disks 35 from the leaf springs 36. It will be apparent that when the shafts are rotated, the disks 35 rotate with them and the edges of the disks bearing on the leaf springs will create resistance to the rotation of the shafts, thereby keeping the ribbon 30 taut as it is wound on one shaft and unwound from the other. The disks 35, however, will readily roll onto and off the leaf springs when inserting and removing the shafts. When the parts are assembled, the leaf springs contacting with the disks 35 will prevent the free rotation of either shaft in order to prevent the ribbon from unwinding from either shaft and becoming loose or slack.

Actuating mechanism is provided for rotating the shafts 31 and 32 to move the ribbon step by step. For this purpose, ratchet wheels 39 are secured on the shafts, preferably near those ends of the shafts opposite to the friction disks 35, and said ratchet wheels are in reversed arrangement, as clearly seen in Fig. 9. Hook pawls 40 are provided to alternately engage the ratchet wheels, and are pivotally suspended, as at

41, from a transverse slide or carrier 42 that is slideable transversely of the plate 18. Said slide is carried by the plate in contact with the bottom surface thereof, the slide having slots 43 receiving screws or headed studs 44 depending from the plate 18, thereby permitting the slide 42 to shift transversely under the plate 18, and said slide is raised and lowered with said plate. The slide 42 is provided intermediate its ends 75 with a depending arm 45, and light coiled springs 46 are confined between the pawls 40 and the arm 45, said arm being located between said pawls. The swinging movements of the pawls 40 away from the arm 45 80 are limited, so that only one pawl can engage a ratchet wheel 39, said pawls alternately engaging the ratchet wheels when the slide 42 is shifted to its opposite transverse positions.

The slide 42 is yieldingly maintained in either of its reversed positions by means of a suitable spring 47. As shown, a wire spring is used, which is of L-shape, being secured at its elbow to the plate 18 at the bottom surface thereof, by a screw or securing element 48, with one arm of the spring bearing against the rim or flange 27. The other arm of the spring 47 has a cam lug or bend 49 to engage a lug 50 on one side of the slide 42. The lugs 49 and 50 cooperate with one another, with the lug 49 bearing against the side of the slide 42 under spring pressure. The lug 50 moves to opposite sides of the lug 49 and when sufficient pressure is applied to the slide 42 to move the lug 50 slightly beyond intermediate position the pressure of the spring 47 will move the slide 42 completely in the direction in which it is started. Thus, the slide 42 will snap beyond intermediate position in either direction, so that the reversal of the slide and actuating mechanism will take place with a sharp quick movement.

The reversing means includes a pair of tripping levers 51 pivoted, as at 52, to the inner side of the block 17 adjacent to which the ratchet wheels 39 are located, and said levers 51 depend from the pivots 52 and have inwardly extending lugs 54 at their lower ends disposed at the opposite sides of the arm 45. A light coiled spring 53 is disposed between the levers 51 in order to swing same apart, and when either lever 51 is swung inwardly the lug 54 thereof will contact with the arm 45 to move the slide 42 in the same direction. The levers 51 have the cams or cam arms 63 at their upper ends which diverge apart upwardly, and a transverse piece 67 is riveted or otherwise secured to the plate 18 at the bottom surface thereof above the levers 51 and has depending lugs 67 cooperable with the cams 63 under certain conditions, as will hereinafter more fully appear, so that when one of the

levers 51 is swung to move its cam 63 under the corresponding lug 67, the depression of the top plate 18 will result in such lever being swung further toward the opposite lever by the pressure which forces the top plate down.

Actuating levers 55 are disposed on the bottom 14, being formed from plates of sheet metal, as shown, and said levers 55 have notches 57 engaging under screws or headed studs 56 secured on the bottom 14 at the opposite sides of the receptacle 29 near that end of the receptacle adjacent to the ratchet wheels 39. The screws or studs 57 retain the levers 55 in position on the bottom 14. Said levers 55 have arms 59 projecting toward the opposite end of the body and provided with upstanding portions 60 disposed at the opposite sides of the two shafts 31 and 32 to be moved toward the side plates 16 when the ribbon is wound on said shafts. The levers 55 have fulcrum or rocker portions 58 to bear against the side plates 16, and said levers have arms 61 projecting toward the levers 51 and provided with upstanding lugs 62 at the opposite sides of the lugs 54, so that when either lever 55 is swung by the outward movement of the portion 60 thereof, the arm 61 of the lever is swung away from the corresponding side plate 16 to swing the corresponding lever 51 toward the opposite side plate or wall.

A transverse guard or shield 64 is secured to and across the end of the receptacle 29 adjacent to the ratchet wheels 39 to prevent the ribbon 30 from shifting longitudinally so as to become entangled with the pawls and ratchet wheels. The bottom 14 has an opening 65 to receive the arm 45 when the plate or impression member 18 is depressed.

The operation of the device is as follows: When the ink is being applied to the type, the lips or portions 25 contacting with the inking roller or rollers will receive ink therefrom, and the springs 23, although permitting the top plate 18 to yield, are of sufficient strength to prevent the full depression of the top plate 18, thereby keeping the inking roller out of contact with the ribbon 30. In other words, the inking roller being of soft rubber or yieldable composition will be forced away from the face of the member 28 and portion of the ribbon thereon, thereby maintaining a clearance between the inking roller of the printing press and the secondary or contrasting color printing means. When the lips or bars 25 contact with the sheet laying against the platen of the press, the platen cannot yield, so that the top plate 18 is depressed or forced to yield so that the edges of the lips or portions 25 move flush with or into the same plane as the faces of the type including the face of the type or secondary impression member 28. The member 28 will make an impression on the sheet

through the ribbon 30, thereby printing the characters of the member 28 on the sheet between the lines or bars printed by the lips 25. Said lines or bars will be printed in the black or regular ink used for the regular printing, while the characters printed by the member 28 will be of the color of the ribbon 30, which may be red, blue or other color in contrast to the color of the ink supplied by the inking roller of the press. It is also possible to have the ribbon provided with strips or bands of different colors, so that the impression made by the member 28 may be of one or more colors.

The ribbon 30 is moved step by step by the full depression of the plate 18, when the impressions are made. Thus, when said plate 18 is depressed the full amount, the pawls 40 are similarly depressed, and that pawl which engages the corresponding ratchet wheel will catch under the next tooth of the ratchet wheel, so that when the plate 18 is released from the platen of the press, the springs 23 raising the plate 18 will result in said ratchet wheel being turned one step. This winds the ribbon slightly on the corresponding winding shaft. In this way, when the plate 18 is depressed successively the ratchet device will wind the ribbon on one winding shaft, so as to feed the ribbon step by step across the type or impression member 28. This presents successive portions of the ribbon for making the impressions, so that the impressions will be uniform. As shown in Figs. 8 and 9, the right hand pawl 40 engages the ratchet wheel 39 of the shaft 32, so that the ribbon is being wound on the shaft 32, said shaft being turned one step for each full depression of the plate 18 when making a printing impression. When one shaft or spool becomes "filled" with the ribbon, the ratchet device is reversed so as to reverse the movement of the ribbon and wind it on the other shaft. Thus, as shown in the drawings, the ribbon is being wound on the shaft 32, with the slide 42 in the right-hand position, as seen in Fig. 9, the lug 50 being at the right of the lug 49 of the spring 47. As the ribbon is wound on the shaft 32 the diameter of the wound portion of the ribbon on said shaft increases, thereby pushing the portion 60 of the corresponding lever 55 outwardly toward the respective side plate 16, and swinging said lever 55 to move the arm 61 thereof toward the opposite side. The right-hand lever 51 (Fig. 9) will therefore be moved toward the left so that its cam 63 will be moved toward the right, the cams 63 being normally between the lugs 67 so as not to be in the paths of movement thereof. The right hand lever 51 is therefore moved gradually as the shaft or spool 32 becomes filled with the ribbon, and when a sufficient amount of ribbon has been wound on said shaft 32, the cam 63 of the right-hand lever

51 will be moved under the right-hand lug 67, so that the next time that the plate 18 is depressed, the right-hand lug 67 will engage the cam 63 of the right-hand lever 51. Said 5 lug will therefore swing the right-hand lever 51 in the same direction (clock-wise as seen in Fig. 10). This movement of the lever 51 is sharp and the movement of the lever under the pressure which depresses the plate 18, 10 such as the pressure of the platen, will be sufficient to reverse the slide 42. Thus, the movement of the right-hand lever 51 toward the left will result in the lug 54 of said lever contacting with the arm 45 and moving said 15 arm toward the left, so that the lug 50 of the slide will snap past the lug 49 of the spring 47. This will reverse the slide 42 and ratchet devices during one depression of the plate 18. The left-hand pawl 40 will now 20 engage the ratchet wheel 39 of the shaft 31, the right-hand pawl 40 having been removed from the ratchet wheel of the shaft 32. Now, the depression of the plate 18 will result in the shaft 31 being rotated to wind 25 the ribbon thereon, and when the shaft or spool 31 becomes full the left-hand (Fig. 9) levers 55 and 51 will shift the slide 42 to the right. This reversal takes place automatically when either shaft or spool becomes 30 full of ribbon.

The screws or threaded studs 57 hold the levers 55 on the bottom 14 and prevent said levers from being displaced longitudinally, but the levers, when moved by the ribbon on 35 the shafts or spools, rock or oscillate on the rockers 58 as fulcrums, said rockers bearing against the side plates 16. When the side plates 16 are removed, the levers 55 may be readily withdrawn, to permit the shafts or 40 spools 31 and 32 to be removed for inspecting the device or replacing the ribbon.

Having thus described the invention, what is claimed as new is:

1. A device of the character described comprising a body, a type high impression member in said body, a top plate disposed over and mounted yieldingly on the body to be depressed by a platen and to force a soft inking roller away from said impression member, said plate having an opening to accommodate said impression member and through which the impression is made when said plate is depressed by the platen, an inked ribbon extending over said impression member below said plate, means for mounting said ribbon for movement within the body, and an operative connection between said plate and means for moving the ribbon step by step by the depression and upward movements of said plate.

2. A device of the character described comprising a body, a type high impression member in the body, a top plate disposed over and yieldingly mounted on said body to force a soft inking roller away from said impression

member and to be depressed by a platen, said plate having an opening to accommodate said impression member and through which the impressions are made when said plate is depressed by the platen, an inked ribbon 70 extending over said impression member below said plate, winding means for said ribbon mounted in the body at opposite sides of said impression member, and an operative connection between said winding means and plate for actuating said winding means to move the ribbon step by step over the impression member when said plate is depressed and raised in making the impressions.

3. A device of the character described comprising a body having a receptacle therein open at the top and bottom, an impression member in said receptacle removable therefrom through the bottom of the body and having its face protruding above the receptacle, a yieldable top plate assembled with the body and having an opening above said impression member through which the impressions are made when said plate is caused to yield by a platen, and an inked ribbon 80 mounted in the body below said plate and extending across the face of said member.

4. A device of the character described comprising an impression member, a ribbon extending across the face thereof, two winding means for winding up the ribbon in opposite directions for the movement of the ribbon in opposite directions, a ratchet wheel connected to each winding means, a yieldable reciprocating member to be reciprocated by a 100 platen when making impressions, a slide carried by the last named member, pawls carried by said slide to alternately engage the ratchet wheels in reversed positions of said slide so that one ratchet wheel and winding means is rotated step by step by the reciprocation of the last named member, and automatic means for reversing the position of said slide at the opposite limits of movement of the ribbon.

5. A device of the character described comprising a body, an impression member mounted in the body, a ribbon extending across the face of the member, two winding means mounted in the body for winding the ribbon thereon in opposite directions for the movement of the ribbon in opposite directions, a yieldable reciprocating member carried by the body to be reciprocated by a platen when making impressions, ratchet wheels connected with said winding means, a slide carried by said reciprocating member and movable to reversed positions, pawls carried by said slide to alternately engage the ratchet wheels in the reversed positions of said slide, and automatic means for reversing said slide including members mounted in the body and having portions to contact with the wound portions of the ribbon on said winding means and arranged to reverse said 125 130

slide when the ribbon is unwound from one winding means and wound upon the other winding means a predetermined amount.

6. A device of the character described comprising a body having removable side plates and slots extending to said side plates, an impression member mounted in the body, shafts seated in said slots, a ribbon wound on said shafts and extending across the face 10 of said member, and means for actuating said shafts, said plates having portions to retain the shafts in position in said slots.

7. A device of the character described comprising a body having end members and removable side plates, said end members having slots extending to the side plates, an impression member mounted in the body, shafts having their terminals seated in said slots, a ribbon connected to said shafts to be wound 20 thereon and extending across the face of said member, and means for actuating said shafts, said plates having fingers extending into said slots and retaining the shafts in position therein.

25 8. A device of the character described comprising a body having a bottom, an impression member mounted in the body, shafts mounted for rotation in the body, a ribbon connected to the shafts to be wound thereon 30 and extending across the face of said member, means for rotating said shafts, friction disks secured to said shafts, and leaf springs having both ends seated on the bottom of the body and having concaved portions between 35 their ends contacting with the lower edges of said disks to frictionally retard the rotation of said shafts.

9. A device of the character described comprising a body having a bottom, an impression member mounted in the body, a ribbon extending across the face of said member, two shafts to which the ribbon is connected to be wound thereon for movement in opposite directions across the face of said member, said body having slots extending to opposite sides thereof receiving said shafts and permitting removal of the shafts from the body, means for actuating said shafts, disks secured on said shafts, and leaf springs having both ends seated on the bottom of the body and having concaved portions between 50 their ends bearing against the lower edges of said disks to retard the rotation of the shafts and to resist the movement of the disks toward said opposite sides of the body.

10. A device of the character described comprising a body having a bottom, an impression member mounted in the body, winding shafts mounted in the body at the opposite sides of said member, a ribbon extending across said member connected to the shafts to be wound thereon, a top plate mounted on the body for up and down movement and having an opening above said impression member through which the impres-

sions are made when said plate is depressed by a platen, spring means for raising said plate, ratchet wheels connected to said shafts, pawls movable with said plate to engage said ratchet wheels for rotating either shaft 70 to wind the ribbon thereon, and automatic means for reversing said pawls for the alternate engagement thereof with said ratchet wheels and including levers mounted on the bottom of the body and having upwardly 75 extending portions at the opposite sides of said shafts to contact with the portions of the ribbon wound on the shafts in order that the swinging of said levers by the unwinding of the ribbon from one shaft and the winding thereof on the other shaft a predetermined amount will reverse the pawls.

11. A device of the character described comprising an impression member, a ribbon extending across the face thereof, winding means for winding up said ribbon for the movement of the ribbon in opposite directions across the face of said member, reciprocatory actuating means to be operated by a platen when making the impressions and arranged to alternately connect with said winding means to move the ribbon step by step in opposite directions, and means controlled automatically at the limits of movement of the ribbon in opposite directions and arranged to be operated by the force of said actuating means during a single movement of said actuating means for reversing the connection between the actuating means and winding means.

12. A device of the character described comprising an impression member, a ribbon extending across the face thereof, two winding means for winding up the ribbon in opposite directions for the movement of the ribbon in opposite directions, ratchet wheels connected to said means, a yieldable reciprocatory member to be reciprocated by a platen when making impressions, pawls movable with the last named member to engage said ratchet wheels for actuating said winding means by the reciprocation of the last named member, and means controlled by the ribbon at the opposite limits of movement thereof 110 and arranged to be actuated by and during a single movement of the last named member for rendering one pawl operative and the other pawl inoperative alternately at the opposite limits of movement of the ribbon so as to reverse the movement of the ribbon.

13. A device of the character described comprising an impression member, a ribbon extending across the face thereof, two winding means for winding up the ribbon in opposite directions for the movement of the ribbon in opposite directions, a ratchet wheel connected to each winding means, a yieldable reciprocatory member to be reciprocated by a platen when making impressions, a

slide carried by the last named member, pawls carried by the slide to alternately engage the ratchet wheels in reversed positions of the slide so that one ratchet wheel and winding means is rotated step by step by the reciprocation of the last named member, and automatic means controlled by the ribbon at the opposite limits of movement thereof and arranged to be operated by and during a single movement of said last named member when making an impression to reverse the position of the slide.

14. A device of the character described comprising an impression member, a ribbon extending across the face thereof, two winding means for winding up the ribbon in opposite directions for the movement of said ribbon in opposite directions, a reciprocatory member to be operated by a platen when making impressions, means for alternately connecting said reciprocatory member with the winding means for moving the ribbon step by step first in one direction and then in the opposite direction, means arranged to be operated by the movement of the reciprocatory member and controlling the second named means for reversing the connections between the reciprocatory and winding means, and means controlling the third named means and having portions to contact with the wound portions of the ribbon on the winding means for automatically controlling the third named means to reverse the connections between said reciprocatory member and winding means when either winding means becomes filled.

15. A device of the character described comprising a body, an impression member mounted therein, a ribbon extending across the face of said impression member, two winding means mounted in the body for winding up the ribbon in opposite directions for the movement of the ribbon in opposite directions, a yieldable reciprocatory member carried by the body to be reciprocated by a platen when making impressions, ratchet wheels connected to said winding means, reversible pawls carried by said reciprocatory member to alternately engage said ratchet wheels for moving the ribbon step by step when said reciprocatory member is reciprocated, cooperative means carried by the body and reciprocatory member operable for reversing said pawls, and means mounted in the body and having portions to contact with the wound portions of the ribbon on the winding means and controlling said cooperative means for bringing said cooperative means into action when the ribbon is unwound from one winding means and wound upon the other winding means a predetermined amount.

16. A device of the character described comprising a body, an impression member mounted in the body, a ribbon extending

across the face of said member, two winding means mounted in the body for winding the ribbon thereon in opposite directions for the movement of the ribbon in opposite directions, a yieldable reciprocatory member carried by the body to be reciprocated by a platen when making impressions, ratchet wheels connected with said winding means, a slide carried by said reciprocatory member and movable to reversed positions, pawls carried by said slide to alternately engage the ratchet wheels in reversed positions of the slide, levers mounted in the body and arranged to move the slides to reversed positions, said levers and reciprocatory member having cooperative portions for swinging said levers to reverse the slide when the levers are moved to predetermined positions and the reciprocatory member is reciprocated, and means controlling said levers and having portions to contact with the wound portions of the ribbon on said winding means for moving said levers to said predetermined positions at the opposite limits of movement of the ribbon when the ribbon is unwound from one winding means and wound on the other winding means a predetermined amount.

17. A device of the character described comprising a body, an impression member mounted therein, a ribbon extending across the face of said member, two winding means mounted in the body for winding the ribbon thereon in opposite directions, a yieldable reciprocatory member carried by the body to be reciprocated by a platen when making impressions, reversible connections between said reciprocatory member and winding means for rotating said winding means step by step when said reciprocatory member is reciprocated and including a member movable to reverse said connections, levers mounted in the body for moving the third named member to reverse the connections, said levers and yieldable reciprocatory member having cooperative portions so that said levers are swung by the depression of the reciprocatory member when the levers are moved to predetermined positions and means controlled by the ribbon at the opposite limits of movement thereof and controlling said levers to move them to said predetermined positions for operation by the reciprocatory member when the ribbon reaches its opposite limits of movement, so as to reverse said connections.

18. A device of the character described, comprising a body, an impression member mounted in the body, a ribbon extending across the face of said member, two winding means mounted in the body for winding the ribbon thereon in opposite directions, a yieldable reciprocatory member carried by the body to be reciprocated by a platen when making impres-

- sions, ratchet wheels connected with said winding means, a slide carried by said reciprocatory member and movable to reversed positions, pawls carried by said slide 5 to alternately engage the ratchet wheels in the reversed positions of said slide, levers mounted in the body and cooperable with the slide for moving the slide to its reversed position, said levers having cams and the reciprocatory member having portions to contact with said cams and move said levers when said levers are moved to predetermined positions, and other levers mounted in the body and controlling the aforesaid 10 levers and having portions to contact with the wound portions of the ribbon on said winding means for moving the first-named levers to said predetermined positions when the last named levers are moved at the opposite limits of movement of the ribbon by the unwinding of the ribbon from one winding means and the winding of the ribbon on the other winding means a predetermined amount.
- 15 19. A device of the character described comprising a body, an impression member therein, a ribbon extending across the base of said member, two winding means for winding up said ribbon in opposite directions for the movement of the ribbon in opposite directions, a yieldable reciprocatory member carried by the body to be reciprocated by a platen when making impressions, a reversible operative connection between the reciprocatory member and winding means for operating either winding means by the reciprocating of said member, and automatic means controlled by the filling of the winding means and controlling said operative connection and arranged to be operated by the force of said reciprocatory member during a single depression of said reciprocatory member when one winding means becomes filled to reverse said operative connection.
- 20 20. A device of the character described comprising a body, an impression member therein, a ribbon extending across the face of said member, two winding means for winding up said ribbon in opposite directions for the movement of said ribbon in opposite directions, a yieldable reciprocatory member carried by the body to be reciprocated by a platen when making impressions, a reversible operative connection between the reciprocatory member and winding means for operating either winding means by the reciprocation of said member, means controlling said operative connection for reversing same operable by the force of said reciprocatory member during a single depression of said reciprocatory member, and means controlling the last named means and controlled by the ribbon wound on said winding means
- for bringing said lastnamed means into operation when either winding means becomes filled.
21. A device of the character described comprising a body, an impression member 70 therein, a ribbon extending across the face of said member, two winding means for winding up said ribbon in opposite directions for the movement of the ribbon in opposite directions, a yieldable reciprocatory 75 member carried by the body to be reciprocated by a platen when making impressions, a reversible operative connection between the reciprocatory member and winding means for operating either winding means 80 by the reciprocation of said member, movable reversing members in the body controlling the operative connection to reverse same, the reciprocatory member having portions to contact with and to actuate said reversing members in predetermined positions thereof, and means controlled by the winding of the ribbon on the winding means to position said reversing members for actuation by the reciprocatory member when 85 the winding means become filled alternately.
22. A device of the character described comprising a body, an impression member 90 therein, a ribbon extending across the face of said member, two winding means for winding up said ribbon in opposite directions for the movement of the ribbon in opposite directions, a yieldable reciprocatory member carried by the body to be reciprocated by a platen when making impressions, a reversible operative connection between the reciprocatory member and winding means for operating either winding means by the reciprocation of said member and including 95 a shiftable member for reversing the connection, a pair of levers mounted in the body and cooperable with said shiftable member to move it in opposite directions, the reciprocatory member having portions to contact with and actuate said levers in predetermined positions thereof, and means controlled by the winding of the ribbon on the winding means to position said levers for actuation by the reciprocatory member when the winding means become filled alternately. 100
23. A device of the character described comprising a body, an impression member 105 therein, a ribbon extending across the face of said member, two winding means for winding up said ribbon in opposite directions for the movement of the ribbon in opposite directions, a yieldable reciprocatory member carried by the body to be reciprocated by a platen when making impressions, a reversible operative connection between the reciprocatory and winding means for operating either winding means by the reciprocation of said member and including 110 a slide carried by said reciprocatory mem- 115

ber, a pair of levers mounted in the body, said slide and levers having cooperable portions for the movement of the slide in opposite directions by the levers to reverse said operative connection, said reciprocatory member having portions to contact with and actuate said levers in predetermined positions thereof, and means controlled by the winding of the ribbon on the winding means 10 to position said levers for actuation by the reciprocatory member when the winding means become filled alternately.

24. A device of the character described comprising a body, an impression member 15 therein, a ribbon extending across the face of said member, two winding means for winding up the ribbon in opposite directions for the movement of the ribbon in opposite

directions, a yieldable reciprocatory member mounted on the body to be reciprocated by a platen when making impressions, ratchet wheels connected to said winding means, a slide carried by said reciprocatory member and movable to reversed positions, pawls carried by said slide to alternately engage 25 said ratchet wheels in reversed positions of said slide, and automatic means controlled by the filling of the winding means and controlling said slide and arranged to be operated by a single depression of said reciprocatory member when either winding means becomes filled to reverse said slide. 30

In testimony whereof I hereunto affix my signature.

JOHN A. WHITTINGTON.
